(57) **CLAIM**

The ornamental design for a lifting apparatus, as shown and described.

DESCRIPTION

FIG. 1 is a front view of the lifting apparatus;
FIG. 2 is a rear view of the lifting apparatus, showing the cable cut away for convenience of illustration;
FIG. 3 is a side connect view of the lifting apparatus;
FIG. 4 is a side connect view with a motor for the lifting apparatus; and,
FIG. 5 is a bottom view of the support footer for the lifting apparatus.

The elements shown in FIGS. 3, 4 and 5 are shown enlarged for clarity of illustration.
